UNITED STATES PATENT OFFICE

CHARLES HAROLD DE WERTH, OF BRONX, NEW YORK

CLOSURE FASTENER OPERATOR

Application filed March 16, 1932. Serial No. 599,285.

This invention appertains to new and useful improvements in closure fasteners, and more particularly to a novel closure fastener of the electrical type.

5 The principal object of this invention is to provide an electrical closure fastener for dumb waiter shaft closures adapted to be operated remotely from a centralized point in a building.

10 Other objects and advantages of the invention will become apparent to the reader of the following specification.

In the drawings:

15 Figure 1 represents a fragmentary vertical sectional view through a dumb waiter shaft showing a closure equipped with the novel fastener.

20 Fig. 2 represents a vertical sectional view through the fastener showing the same in fastened position.

Fig. 3 represents a vertical sectional view 25 through the fastener showing the fastener in unfastened position.

Fig. 4 represents a perspective view of the keeper.

30 Fig. 5 represents a diagrammatic view disclosing the electrical connection between the electrical devices involved.

Referring to the drawings wherein like numerals designate like parts, it can be seen that numeral 5 represents the shaft of a dumb waiter, numeral 6 representing the dumb waiter elevator bulb operative therein.

35 Numeral 7 generally refers to the fastener, while numeral 8 denotes the closure of which may be any number and it is also to be understood, that the dumb waiter 6 may serve more than one apartment or suite of rooms on a given floor, in which instance, all of the 40 closures 8 affording communication or access to the particular dumb waiter on the same floor can be operated simultaneously. (See Fig. 5).

45 As is apparent in Figs. 1 to 3 inclusive, the keeper (see Fig. 4) generally referred to by numeral 9 includes a plate 10 having openings 11 therein through which fastening means can be disposed for securing the plate to the closure 8. Extending from this plate 10 is the 50 shank 12 having an upstanding head 13 at its

outer end. This head 13 has a beveled portion 14 on the outer end thereof.

The fastener proper denoted by numeral 15 in Figs. 2 and 3 includes a casing 16 and a removable closure 17 (see Fig. 1). The securing element consists of an arm 18 having a depending head 19 at its free end, and a depending leg 20 at its pivoted end which merges into an inwardly diverged extension 21. This extension 21 is provided with an inwardly disposed formation 22 thereon having a beveled portion 23 which is normally in the path of the beveled portion 14 of the head 13 on the keeper generally referred to by numeral 9.

60 Numeral 24 represents an electromagnet with which the swingable armature 25 is associated. This armature 25 is a boss 26 thereon and is connected to the di-electric block 27 by the leaf spring 28.

65 As is clearly shown in Fig. 5, numeral 29 represents a suitable source of energy such as a battery or the like on one side of which extends a lead 30 to the switch arm 31. Extending from contact 32 located adjacent the switch blade, and with which the switch blade is selectively engageable on the conductors 33, each of which extends to one side of an electro-magnet 24.

70 If there are more than one of the electro-magnetic fasteners on each floor of the building, these can extend from the conductors 33 to the several electromagnets. Numeral 35 represents the negative side of the system and branches 36 can extend therefrom on different floors of a building, to connect to the negative sides of the electro-magnets 24.

75 It can now be seen, that normally, the head of the arm 18 is engaged with the head 13 of the keeper 9. The spring 28 of the armature 25 maintains the armature 25 elevated so that the boss 26 will be in advance of the extension 21. This is against the tension of the spring 36 which is convoluted about the pivot pin 37 of the arm 18.

80 It can now be seen, that when the electro-magnet 24 is energized by actuating the switch blade 31 through engagement of the contacts 32 (this being performed by the janitor or other house servant) the armature 25

will be attracted, resulting in the release of the arm 18. The spring 36 will now swing the arm upwardly and as this occurs, the beveled portion 23 of the formation 22 will 5 ride against the beveled portion 14 of the head 13 on the keeper 19 and in so doing will exert pressure sufficient to automatically open the closure 8.

Obviously, when the closure is again closed 10 the beveled portion 14 will wipe against the beveled portion 23 on the formation 22 with the result that the diverged extension 21 will be swung backwardly to engage behind the force 26 on the armature 25, the electro- 15 magnet 24 now being de-energized.

While the foregoing specification sets forth the invention in specific terms, it is to be understood that numerous changes in the shape, size and materials may be resorted to 20 without departing from the spirit and scope of the invention as claimed hereinafter.

Having thus described my invention, what I claim as new is:—

A fastener operator comprising a keeper 25 having an upstanding head beveled on its outer side, a swingable arm having a depending head, a projection underlying the head on the arm, said projection being provided with a beveled portion on the same plane with the 30 bevel of the keeper head, and located inwardly of the innermost side of the head of the arm, and a spring for normally maintaining the arm urged to a position maintaining the projection with its beveled portion opposed to 35 the beveled portion of the head of the keeper and in the path of the keeper.

In testimony whereof I affix my signature.
CHARLES HAROLD DE WERTH.
